[57] **CLAIM**

The ornamental design for a nose cone for a tool, as shown and described.

DESCRIPTION

FIG. 1 is a perspective view of a nose cone for a tool showing my new design, the broken line portions of the disclosure forming no part of the claimed design;

FIG. 2 is a side elevational view thereof;

FIG. 3 is a top plan view thereof; and,

FIG. 4 is a bottom plan view thereof.
